PACKER

James P. Bradner, San Francisco, Calif.

Application February 21, 1940, Serial No. 320,148

8 Claims. (Cl. 166—1)

This invention relates to a packer, and especially to that type of packer known as a "formation packer."

In drilling oil wells it is often necessary to seat a packer in an open hole. This is particularly true when a new or different formation is encountered during the drilling of a well, and it is desired to obtain a sample of oil, if any, in that stratum or formation. At such times a hole of the required diameter has already been drilled, and in order to make a test of the formation a hole of relatively small diameter is drilled down into the formation for exploration or testing purposes. This smaller hole is commonly referred to as a "rathole." At the juncture between the well bore and a rathole a tapering seat or square shoulder is formed, the larger diameter of which is represented by the well bore and the smaller diameter by the rathole.

In drilling both the main well bore and the rathole, it is possible that high pressure gas or oil strata may be encountered which would tend to blow the hole. Hence, a heavy drilling fluid, usually called "mud" is employed to prevent blowing. This mud fills the entire well bore and the rathole, and when a rathole packer, together with a string of testing tools, is lowered to seal off the formation and to obtain a sample therefrom, the pressure in the rathole or below the packer may drop considerably while the mud column will maintain its high pressure, thereby tending to leak by the packer and cut the seat of the rathole to such an extent that the packer loses its seal. For this reason it is important to drive or force the packer into the rathole seat with considerable pressure in order that no leakage may occur, and consequently great difficulty is often encountered in removing the packer and connected string of testing or sampling tools after a sample has been taken.

The object of the present invention is generally to improve and simplify the construction and operation of tools of the character described, and particularly to provide a rathole packer which may be forced or firmly driven into the rathole seat prior to the taking of a sample, to form a substantially leakproof seal, and thereafter be readily released and removed when the sample has been taken. The packer and the tools employed in connection therewith are shown by way of illustration in the accompanying drawing, in which:

Fig. 1 is a vertical section of a well bore, showing the packer and the testing tools in position to take a sample from a stratum or formation to

be tested. A portion of the packer is shown in section in this view.

Fig. 2 is an enlarged vertical longitudinal section of the sampling tool, together with a portion of the string or tubing from which it is suspended;

Fig. 3 is an enlarged vertical longitudinal section of the rathole packer;

Fig. 4 is an enlarged view of a packer sleeve;

Fig. 5 is an enlarged cross section of the packer sleeve prior to contraction; and

Fig. 6 is a similar section showing the packer sleeve after contraction.

In the drilling of oil wells, and in operations incident to testing the productivity of different formations which are being penetrated, it is desirable to provide apparatus which may be readily lowered into the well through the drilling mud contained therein, without the necessity of removal of the mud. Also, it is desirable to seal off the formation to be tested from the mud within the well above the seal, so that a sample from the formation may be withdrawn without admixture of mud. The apparatus employed is usually termed a testing or sampling tool. It carries a packer near the lower end which seats in and seals off the formation; and when seated, valves in the tool are opened and later closed to admit and then entrap a sample of the fluid from the formation being tested. Thereafter the string or tubing and the testing tools suspended therefrom are removed from the well, and the entrapped sample of fluid may then be drained out and tested.

The present invention provides an improved form of packer for sealing off the formation to be tested, and while the packer may be used with different types of testing or sampling tools, a suitable form of tool is shown by way of illustration, and will be only briefly described, as a complete description of its structure will be found in Patent No. 2,073,107, entitled "Well testing method and apparatus," issued March 9, 1937, to M. O. Johnston.

Referring to the drawing in detail, A indicates a packer; B, a mud by-passing valve; C, a main valve; D, a trip valve; E, a portion of the upper drill string or tubing from which the tools are suspended; and F, an intermediate section or string of tubing which is provided for the reception and entrapment of the sample to be taken.

When a well is being drilled and a certain formation is encountered which it is desired to test, a hole H of the required diameter will already have been drilled, and in order to make a test

of the formation, a hole J of relatively small diameter is drilled down into the formation. This smaller hole is commonly referred to as a rat-hole. At the junction between the main well bore or hole and the rathole, a tapering seat K is formed, or a shoulder, and it is this seat into which the packer A is forced when the formation is to be sealed off from the mud in the well and the strata above.

Due to the high pressure exerted on the packer by the hydrostatic head of the mud above the packer, particularly in a deep well, there is considerable danger of mud leaking by the packer and cutting away the rathole seat, this being particularly true if a considerable pressure reduction takes place below the packer while a sample is being taken. It is for this reason that the packer must be firmly seated during the taking of a sample, and due to the firm seating it often happens that considerable trouble is encountered when the packer is to be removed. The trouble of removal will be entirely overcome by the use of the packer here illustrated.

The packer consists of a head member 2 which is secured by means of a threaded coupler 3 to the lower end of the valve body B containing the mud by-passing valve. Secured to the head 2 by a threaded connection 4 is a tube 5, and slidably mounted thereon is a sleeve 6 which carries the packer A. The sleeve 6 has a flange 7 formed at its upper end to act as a retainer for a series of packing discs 8 which are slipped over the sleeve. The lower end of the sleeve is threaded to receive a washer 9 and a nut 10, and by these the packing discs are held in compressed condition.

Formed in the sleeve 6 intermediate the flange 7 and the lower threaded end are a series of slots 11 which serve the function of permitting contraction or reduction in the diameter of the sleeve, and consequently the packing discs 8, when the packer is to be removed from its seat, as will hereinafter be described. The upper end of the tube 5 (see Figs. 1 and 3) presents an exterior diameter which snugly fits the interior of the sleeve 6, thus preventing contraction of the sleeve 6. The lower end of the tube, on the other hand, is reduced in diameter, as indicated at 5a, to permit contraction of the sleeve when the packer is to be released and removed from its seat. To permit such contraction as heretofore described, the tube 5 is pulled upwardly in the sleeve until a collar 12 on the lower end thereof engages the lower end of the sleeve 6. When this position is assumed, the reduced diameter of the tube 5a will register with the slots 11, permitting the sleeve wall to yield inwardly and assume the contracted position shown in cross section in Fig. 6. The reduction in diameter thus provided will be considerable, and the packer, which has previously been firmly driven, and which would present serious difficulty when removal thereof is attempted, is in this instance readily removed due to the amount of contraction provided.

In actual practice, when the rathole has been drilled and a sample is to be taken, the packer A, the mud by-passing valve B, the main valve C and the trip valve D are assembled and connected at the surface, and by means of the drill string or tubing E is lowered into the well. During the lowering operation the packer A will assume the position shown in Fig. 3, as it is held in this position by a pair of hooked pins 30 secured to the collar 2, and this position will be

maintained until the packer reaches its seat, when it will be forced tightly into the seat by the weight and downward pressure of the tool string. During the lowering movement and while the packer is being forced into its seat the larger upper end 5 of the tube is in register with the slotted sleeve 6, and as the larger end of tube 5 snugly fits the interior of the sleeve, contraction can not take place while the packer is forced into the seat.

During the lowering movement through the mud, by-pass valve B is automatically maintained in open position, that is, with the ports 15 in register with the annular space 16 and the outlet ports 17, so that mud may pass freely through the anchor tube 18, the tube 5, the head 2, the passage 19, and ports 17 and 15, but when the packer becomes seated, sleeve 20 in which the ports 15 are formed telescopes and moves downwardly in the valve body B to the position shown in Fig. 2, thereby closing the bypass. Valves C and D are maintained in closed position during the lowering movement, but when the packer has become firmly seated, valve C opens automatically on taking the weight of the drill string; valve D, on the other hand, is opened by manipulation from the surface, and fluid from the formation to be tested is thus free to flow up through the anchor tube, the connected tube 5 and the by-pass valve, which is now closed. Thereafter the fluid flows through the main valve C into the intermediate string or tubing F, which is of sufficient length and capacity to entrap and retain the quantity of fluid required for testing or sampling purposes.

After the sample has been taken the whole string of tubing E, together with the sampling tool and packer, will have to be raised and removed from the well. The moment raising movement commences, valve C closes, thereby entrapping the fluid sample; the by-pass valve B opens, and head 2 through means of the hooked pins 30 will exert an upward pull on the packer, but as this is firmly seated the hooks will yield or straighten out, thereby releasing the packer and permitting the tube 5 to be pulled upwardly through the packer until the collar 12 engages the same. The reduced diameter 5a of the tube now registers with the packer sleeve 6, and as the pull continues the slotted wall of the sleeve yields and contracts, thereby permitting the packing discs to contract, and the packer is thus released with comparative ease, and the entire string of tubing and tools is readily removed.

When the packer is being forced into the rathole seat the packing gaskets or discs 8 tend to assume a dished or curved shape, such as indicated by the dotted line a—a in Fig. 3. Hence when the packer is being removed they tend to straighten out and thus exert an inward force which is utilized to collapse or contract the slotted sleeve 6. In Figs. 5 and 6 the sleeve is shown as surrounded by two overlapping semi-circular sections of thin sheet metal, as indicated at 25 and 26. These sections of metal cover the slotted portion of the sleeve 6 and are provided for the purpose of preventing portions of the packing from being forced into the slots 11 and thereby preventing their closing when the sleeve is to be contracted.

By referring to Fig. 3 it will be noted that the head 2 is provided with recesses 31 on opposite sides and that the hooked pins 30 are placed in the recesses and secured at their upper ends in said recesses. Also it should be noted that the

hooked pins are made of heavy wire or small-diameter rods which have ample strength to secure the packer to the head 2 during the lowering operation, but when the packer is to be released and pulled out of its seat, they are ineffective to do so, as the hooked ends will yield and pull out of the hole formed in flange 1, thereby permitting upward movement of tube 5 and transfer of the entire pulling operation to the collar 12 formed on the tube. The provisions of recesses for the reception of the hooked pins is of importance, as the hooked pins might otherwise project; projections of any character are undesirable as they tend to tear or dig into the walls of the well bore and damage the same.

In summary it is to be understood that the packer A, consisting as here shown, of the packing medium 8 and the slotted sleeve 6, is to be treated and considered as a unit; this packer being characterized by the provision of a contractible seal with a tapering exterior and having a central passage in it, of uniform diameter throughout the length of the packer. Essential to the operation of the packer is the rigid tube which presents two diameters, one which snugly fits the packer to prevent inward movement of the same when being seated in the formation, and a second portion of reduced diameter to provide an annular space so that the packer may contract when it is to be removed from the formation. The packing medium A is at no time expanded. It is provided with a tapering exterior surface, which is set by the great weight of the tool string into the seat a—a of the formation to form a seal. When so seated, the packer is compressed, and, therefore, tends to yield inwardly, or in other words, to become reduced in diameter. Such reduction in diameter must be properly limited when the packer is being set or seated into the formation to insure a tight seal. To limit this tendency to inward yielding movement while the packer is in its operative position in the well, the enlarged diameter portion of the tube 5 fits snugly within the packer. When the packer is to be removed, the rigid tube is pulled upwardly and the portion 5a of smaller diameter will thus enter the central passage of the packer. There will thus be provided an annular space around the portion 5a which will permit inward contraction of the packer, and thereby permit it to be released when it is to be removed.

While certain features of my invention have been more or less specifically described and illustrated I nevertheless wish it understood that changes may be resorted to within the scope of the appended claims.

Having thus described and illustrated my invention, what I claim and desire to secure by Letters Patent is:

1. A well packer of the character described comprising an elongated sleeve surrounded by a packing medium, said sleeve being of uniform diameter throughout its length and having a yieldable annular wall, a rigid tube extending through the sleeve and slidable therein, said tube presenting a uniform diameter throughout approximately half of its length which fits the interior of the sleeve to prevent yielding of the sleeve wall, and a second portion of reduced diameter throughout the remainder of its length, which provides space to permit inward yielding of the sleeve wall, and means for connecting one end of the rigid tube with a tool string whereby it may be manipulated to position either the

larger or the smaller diameter portion within the sleeve.

2. A well packer of the character described comprising an elongated sleeve surrounded by a packing medium, said sleeve being of uniform diameter throughout its length and being provided with a plurality of slots which extend throughout the greater portion of its length to form a yieldable wall, a rigid tube extending through the sleeve and slidable therein, said tube presenting a uniform diameter throughout approximately half of its length which fits the interior of the sleeve to prevent yielding of the sleeve wall, and a second portion of reduced diameter throughout the remainder of its length, which provides space to permit inward yielding of the sleeve wall, and means for connecting one end of the rigid tube with a tool string whereby it may be manipulated to position either the larger or the smaller diameter portion within the sleeve.

3. A well packer of the character described comprising an elongated sleeve, said sleeve being provided with a plurality of spaced slots which extend substantially from end to end of the sleeve, a flange on one end of the sleeve, a nut on the opposite end, a plurality of packing discs carried by the sleeve, and maintained under compression by the flange and nut, a rigid tube extending through the sleeve and slidable therein, said tube presenting a diameter throughout a portion of the length which fits the interior of the sleeve to prevent yielding of the sleeve wall, and a second portion of reduced diameter which provides space to permit yielding of the sleeve wall, and means for connecting one end of the rigid tube with a tool string whereby it may be manipulated to position either the larger or the smaller diameter portion within the sleeve.

4. A well packer of the character described comprising an elongated sleeve, said sleeve being provided with a plurality of spaced slots which extend substantially from end to end of the sleeve, a flange on one end of the sleeve, a nut on the opposite end, a plurality of packing discs carried by the sleeve, and maintained under compression by the flange and nut, a rigid tube extending through the sleeve and slidable therein, said tube presenting a diameter throughout a portion of the length which fits the interior of the sleeve to prevent yielding of the sleeve wall, and a second portion of reduced diameter which provides space to permit yielding of the sleeve wall, means for connecting one end of the rigid tube with a tool string whereby it may be manipulated to position either the larger or smaller diameter portion within the sleeve, and a collar on the reduced end of the rigid tube engageable with the sleeve to exert an upward lifting force when a raising movement is imparted to the tool string.

5. A well packer of the character described comprising an elongated sleeve surrounded by a packing medium, said sleeve having a yieldable annular wall, a rigid tube extending through the sleeve and slidable therein, said tube presenting a diameter throughout a portion of its length which fits the interior of the sleeve to prevent yielding of the sleeve wall, and a second portion of reduced diameter which provides space to permit yielding of the sleeve wall, a head member secured to one end of the rigid tube to connect the tube with a tool string, whereby it may be manipulated to position either the larger or the smaller diameter portion within the sleeve, and

a detachable connection formed between the head member and the sleeve.

6. A well packer of the character described comprising an elongated yieldable packing member permissibly yieldable under external pressure, said member presenting an exterior tapering surface and having an interior central passage of uniform diameter throughout its length, a rigid tube extending through the central passage of the packing member and being slidable therein, said tube presenting a uniform diameter throughout approximately half its length, to fit the central passage of the packing member and to prevent yielding of the said member, and a second portion of reduced diameter throughout the remainder of its length, which provides space to permit inward yielding of the packing member, and means for connecting one end of the rigid tube with a tool string whereby it may be manipulated to position either the larger or the smaller diameter portion within the packing member.

7. In a well packer the combination with an elongated, inverted conical member comprising the packing medium and yieldable under external pressure, of means including a rigid tube extending through said conical member and slid- able therein, said tube having a portion of its length of uniform diameter making a snug fit with the inner diameter of said member to resist

contraction of the packing medium when seated in position in the well, and having the remaining portion of its length of uniform but substantially less diameter than the inner diameter of said packing member to permit reduction in diameter and ready removal of said packer when the tube is positioned with said portion of lesser diameter within the packing member.

8. In a well packer having an elongated, radially contractible sleeve surrounded by a conical packing medium which is yieldable under external pressure, a rigid tube extending through said sleeve and slidable therein, a cylindrical portion of the tube making a snug fit with the inner diameter of said sleeve, another cylindrical portion of its length being substantially less in diameter than the inner diameter of said sleeve, a head member secured to one end of said tube for connection to a tool string and arranged for axial movement of said tube within said sleeve, and a detachable connection formed between said head member and said sleeve, said connection being broken on the upward movement of the tube and permitting said sleeve to contract about the portion of lesser diameter of the tube by external pressure when said lesser diameter tube portion is moved into the space within the packing member.
